UNITED STATES PATENT OFFICE.

HARRY WEARNE, OF RIXHEIM, GERMANY.

DESIGN FOR WALL-PAPER.

SPECIFICATION forming part of Design No. 33,902, dated January 8, 1901.

Application filed December 18, 1900. Serial No. 40,314. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a section of wall-paper embodying the features of my design.

The leading features of the design consist in a lozenge-shaped panel, a bouquet produced upon the panel, and a network surrounding the panel.

The minor features of the design consist in floral sprays at top and bottom of the panel, a foliate border within the panel, a foliate border for the upper portions of the network,

a floral festoon bordering the lower portions of the network, floral festoons which extend from an end portion of the panel out beyond opposite sides, and foliate sprays having ribbon decorations and located at the sides of the panel adjacent to one end.

Having thus described my invention, I claim as new and desire to secure by Letters Patent—

The design for wall-paper as herein shown and described.

In testimony whereof I have signed my name to this specification in the presence of two subscribing witnesses.

HARRY WEARNE.
